UNITED STATES PATENT OFFICE.

ISAIAH L. ROBERTS, OF LOCKPORT, NEW YORK.

MANUFACTURE OF WATER, ACID, AND ALKALI PROOF ARTICLES.

No. 921,000.

Specification of Letters Patent.

Patented May 11, 1909.

Application filed October 3, 1907. Serial No. 395,663.

To all whom it may concern:

Be it known that I, ISAIAH L. ROBERTS, a citizen of the United States, and resident of Lockport, in the county of Niagara and 5 State of New York, have invented certain new and useful Improvements in Manufacture of Water, Acid, and Alkali Proof Articles, of which the following is a specification.

- 10 My invention relates to articles of wood, wood-pulp, strawboard or other woody material, to be used with acids or alkalies or both, and has for its object to provide an effective process for rendering such articles 15 liquid proof and also resistant to the attacks of acids and alkalies.

Heretofore numerous attempts have been made to utilize wood, woodpulp, etc., for articles to be used with acids and alkalies, 20 for example as containing receptacles or vessels for the same. A common method for the purpose is to coat the surface of the article, or to impregnate the article as deeply as possible, with acid and alkali resisting material; but it has been found that 25 after an article so treated has been in use for a more or less short time the chemical, especially if it be an acid, attacks the ends of the fibers at the contact surface, and following these fibers soon permeates the article and greatly impairs it or renders it entirely useless.

My present invention also involves impregnation of the article as deeply as possible, but in a novel manner, whereby a marked alteration of the character of the woody material is effected, with the result that the finished article is practically unattackable by acids and alkalies.

- 40 In carrying out my invention in a simple way the article to be treated is immersed in a bath of resistant material such as resin, stearic acid, sulfur, linseed oil, paraffin, etc., the temperature of which is high enough to 45 partially carbonize the article. The partial carbonization, which is not carried far enough to materially impair the strength of the article, renders the material thereof porous, into the pores and interstices of 50 which the resistant substance of the bath enters. On removing and cooling the article the permeating or impregnating material solidifies in the pores, leaving the article liquid-proof and thoroughly resistant. 55 If the article to be treated is bulky or thick, the bath is preferably at low tem-

perature when the article is placed therein, after which the temperature is raised until the carbonization has proceeded as far as desired. The temperature is then reduced 60 to a point slightly above the melting point of the bath, after which the article is removed and allowed to drip and cool. In this way there is little if any absorption of the bath liquid until the water and gases 65 liberated during the carbonization are all evolved, since the evolution thereof goes on while the temperature is rising and so prevents the liquid from entering the pores. But when the temperature falls the evolution ceases and the liquid immediately enters, and penetrates to a greater depth than would be the case if the temperature remained high.

If desired the treatment may take place 75 in a partial vacuum, thus making the process more rapid. In a vacuum the gases are evolved more rapidly, and on restoration of atmospheric pressure the bath liquid is forced into the pores deeply and quickly. 80 Furthermore, the temperature need not be so high in a vacuum, since in a vacuum decomposition, that is, carbonization, takes place at a lower temperature.

A convenient apparatus for practicing 85 the invention is illustrated in the annexed drawing, which shows the same in vertical section.

The furnace A is of brick, inclosed in an iron sheathing B. In the furnace is an iron 90 vessel C, of suitable size, to which are connected a valved exhaust pipe D, for connection with an air pump, and a valved inlet pipe E by which air may be admitted at the proper time. The vessel is heated by suitable gas burners F.

In the vessel C is the carbonizing and impregnating bath, indicated by G. As previously stated, various substances can be used for the purpose; but the substance or 100 substances used should be capable of withstanding the necessary carbonizing temperature without decomposition or prohibitory volatilization. Among such may be mentioned stearic acid, the resins, paraffin wax, 105 sulfur, linseed oil, and asphaltum, and mixtures of two or more of these. Asphaltum, for instance is too thick or viscous when heated to enter the pores of the article readily, but paraffin or resin may be mixed 110 with the asphaltum in sufficient quantity to give the desired fluidity. The article will

be waterproof if any of the substances mentioned be used, and also acid and alkali proof if sulfur or paraffin be used. If stearic acid or resin, or a mixture of asphaltum and resin, be employed, the article will be acid proof but not alkali-proof, since the substances mentioned saponify in alkali. The articles, which are of course lighter than the bath even when thoroughly impregnated, are kept submerged by a suitable weight, such as perforated iron plate H. Hollow articles, such as the pails I, tubes J, cup K, etc., as shown, should be placed on their sides, so as to promote free circulation of the bath into and out of them. Sheets or plates, as L, may be placed below. An air-tight cover, M, is now placed on the vessel C, and the air exhausted through pipe D. As the articles become heated the evolution of air and gases from the articles takes place rapidly. When the articles are sufficiently carbonized the vacuum is relieved by opening the inlet pipe and closing the exhaust pipe, whereupon the absorption of the bath liquid by the pores and interstices of the articles is completed, the increased pressure causing the liquid to permeate the articles thoroughly, as will be readily understood. The articles are then removed, and allowed to drip and cool. In the case of bulky or thick-walled articles the exhaustion of the gases above the bath may be repeated several times, or the air-pump kept at work during the treatment, to insure complete permeation. Likewise the temperature may be low, say but slightly above the melting point of the bath, at the start, then raised to the carbonizing temperature, and then lowered, as previously mentioned.

40 The temperature required for the carbonization, and the length of time the articles should be treated *in vacuo* and under atmospheric pressure will depend in general upon the size of the articles and the material composing the same, and for particular materials and conditions can best be determined by trial. Tests can easily be made with desired materials and the conditions necessary for the proper degree of carbonization and permeation can be readily found.

55 Articles treated as above described are completely liquid-proof and are practically unattackable by acids and alkalies. At the same time the treatment is inexpensive, quick, and not difficult to practice, requiring only reasonable care and attention on the part of the operator.

What I claim is:

60 1. The herein described method of treating articles composed of woody material to

render the same water, acid, and alkali-proof, which consists in partially carbonizing the article in a heated bath of water-proofing and resistant material and permitting the material of the bath to permeate 65 the article.

2. The herein described method of treating articles composed of woody material to render the same water, acid, and alkali-proof, which consists in immersing the 70 article in a bath of resistant material, heating the bath till the article therein is partially carbonized, and permitting the material of the bath to permeate the article.

3. The herein described method of treating articles composed of woody material to render the same water, acid, and alkali-proof, which consists in immersing the article in a bath of water-proof and resistant material, heating the bath till the article 80 therein is partially carbonized, then lowering the temperature of the bath with the article immersed therein.

4. The herein described method of treating articles composed of woody material to render the same water, acid, and alkali-proof, which consists in immersing the article in a bath of water-proof and resistant material, producing a partial vacuum 85 above the bath and heating the bath with the article therein till the article is partially carbonized, and relieving the vacuum above said bath.

5. The herein described method of treating articles composed of woody material to render the same water, acid, and alkali-proof, which consists in immersing the article in a bath of resistant material, producing a partial vacuum above the bath and heating the bath till the article therein is 100 partially carbonized, and relieving the vacuum and lowering the temperature of the bath.

6. The herein described method of treating articles composed of woody material to render the same water, acid, and alkali-proof, which consists in immersing the article in a bath of water-proof and resistant material liquefied by heat, partially carbonizing the woody material of the 105 article while in the bath and permitting the liquefied material of the bath to permeate the partially carbonized article, then removing the article from the bath and allowing the absorbed material of the bath to harden by cooling.

ISAIAH L. ROBERTS.
